UNITED STATES PATENT OFFICE.

WILLIAM J. CHERRY, OF NEW YORK, N. Y.

PLAYER-PIANO.

1,166,185.

Specification of Letters Patent. Patented Dec. 28, 1915.

Application filed December 19, 1914. Serial No. 878,138.

To all whom it may concern:

Be it known that I, WILLIAM J. CHERRY, of New York, in the county of New York and State of New York, have invented certain new and useful Improvements in Player-Pianos; and I do hereby declare the following to be a full, clear, and exact description of the invention, such as will enable others skilled in the art to which it appertains to make and use the same.

My invention relates to an improvement in player pianos and more particularly to that type of case for a piano mechanism which includes means for controlling treadles which operate the bellows, and means for controlling the doors which cover the treadle and tracker bar openings when the player mechanism of the piano is in the inoperative position.

One object of my invention is to provide controlling means for synchronously operating the treadles and doors in consecutive order, so that, by a movement of the controlling means, the doors concealing the treadles and tracker bar will be opened and the treadles will be projected into the operative position or vice versa.

Another object of my invention is the provision of a key lock and means for concealing the manually operated expression levers, both of these being operable from the treadle and door operating mechanism and being operable simultaneously therewith.

A still further object of my invention is the provision of suitable lost motion connections in the treadle and door operating mechanism, so that the doors will be open before the treadles begin to move, or in closing the instrument, the treadles will move into the inoperative or retracted position before the doors begin to close.

A still further novel feature resides in the provision of means engaging only one of a series of connecting door sections for closing the treadle and tracker bar openings, so that when one door section is moved, the other door section will be correspondingly moved in unison therewith.

Other features of novelty will be more fully described in connection with the accompanying drawing, forming a part of this specification, and will be more particularly pointed out in and by the appended claims.

In the drawings:—Figure 1 is a front elevation view of a piano case embodying the preferred form of my invention, and having

portions thereof broken away for the purpose of showing details. Fig. 2 is a sectional elevation through the piano case shown in Fig. 1 and taken on the line A—B 60 of Fig. 1. Fig. 3 is an enlarged sectional view on the line C—D of Fig. 1, showing in detail the preferred form of mechanism. Fig. 4 is a rear elevation of one of the driven members showing the key lock and 65 pedal operating connections attached thereto. Fig. 5 is a face view of the gear which meshes with the driven gear member shown in Fig. 4. Fig. 6 is a face elevation view of the toothed quadrant which meshes with the 70 gear driven member for operating the treadle doors. Fig. 7 is an elevation view showing the toothed quadrant in meshed relation with its driving element. Fig. 8 is a view of one preferred form of cable connection, for use in connecting the door sections. Fig. 9 is a perspective view showing the door structures comprising connected door sections and the door, treadle, key lock and key slip operating mechanism. 80 Fig. 10 is a view similar to Fig. 9 but showing one modified form of operating mechanism. Fig. 11 is a section view taken on a transverse plane and showing in detail the modified form of my invention. Figs. 12 85 and 13 are details of the two preferred types of lost motion devices which may be employed in the modified form. Fig. 14 is a detail view showing the links comprising the modified form in separated relation to 90 better illustrate the manner of their co-operation.

Like characters of reference designate similar parts throughout the different figures of the drawings.

I will now proceed to describe the specific forms of my invention as illustrated in the drawings.

Referring particularly to Figs. 1 to 9 inclusive, in which I have illustrated that 100 form of my invention which includes toothed gear means for imparting motion to the doors, treadles, key lock and key slip, 1 represents the usual type of piano instrument case including upper and lower panel 105 walls 2 and 3 respectively, having, in this case, since the instrument is of the player piano type, a tracker bar opening 4 in the upper panel 2 and a treadle opening 5 in the lower panel 3. As is usual in player piano 110 constructions the bellows 6 are disposed within the case 1 behind the lower panel 3,

These bellows are supported by a bracket 7 on a step piece 8, and the step piece 8 is provided with an extension 9 to which is pivoted a bell crank lever 10 having connection 5 with a support 11 to which are pivoted the treadles 12 for operating the bellows 6 connected to the treadles by the link 13. These treadles are so mounted on the bracket 9 as to be foldable within the case 1 through the 10 opening 5 in the lower panel 3.

On the key bed 14 of the piano case 1 is hung a bracket 15 in which is journaled a shaft 16 squared on its upper end as shown at 17 and carrying on its lower end the 15 superposed concentric bevel gears 18 and 19. The gear 19 is keyed or otherwise secured to the shaft 16 and carries a pin 20 which engages an arcuate slot 21 in the gear 18, the gear 18 being loosely mounted on the shaft 20 17, thus providing a lost motion connection or drive between the two gears 18 and 19. A lever 22 fits on the squared end 17 of the shaft 16 and is provided with a handle 23 for manually moving the said lever 22. The 25 gear 19 meshes with a gear 24 having its axis of rotation at right angles to the axes of rotation of the gears 18 and 19. The gear 24 is provided on its plain surface with a crank pin 25 upon which is journaled a connecting rod 26, the lower end of which is connected at 27 with the bell crank lever 10; thus it will be seen that if the lever 22 is moved to rotate the gear 19 in the direction indicated by the arrow in Fig. 9 the treadles 30 35 12 will be swung upwardly through the opening 13 into a retracted or inoperative position within the case 1, if the lever be moved in a direction opposite to that of the arrow shown in Fig. 9 the treadles will be 40 projected through the opening 5 into an operative position as shown in Figs. 2 and 9.

In constructing player pianos it has been found advisable to incorporate a key lock for locking the keys when the piano is being 45 automatically operated, also it has been found advisable to provide a key slip for the manually operated expression levers 28 when the automatic mechanism of the player piano is not in use, however these expression 50 levers 28 must be exposed when the piano is being operated automatically, therefore on the front portion of the key bed 14 I have provided a key slip 29 hinged at 30 and suitably hollowed out at 31 for concealing the expression levers 28, and this key slip is connected at its free end with the free end of the key lock 32 by a link 33, the key lock 32 being hinged at 34 so that it may be operated to the key locking position as shown in 55 Fig. 2 or to the key free position. Since these two elements, namely, the key slip and the key lock are connected by means of the link 33 it will be seen that if the key lock 60 is operated to the key locking position, as shown, the key slip will be turned down

into the position shown in Fig. 2 and the expression levers exposed to view for manual operation, whereas, if the key lock 32 is operated to the key free position, the key slip 29 will be turned up to the vertical position, thereby concealing the expression levers 28 from view. Now in order to operate these elements, namely, the key lock 32 and key slip 29, simultaneously with the operation of the treadles 12 and from the same 70 source, the key lock 32 has connected thereto a lever 35 and this lever 35 is connected to a second crank pin 36 on the plain face of the gear 24, thus when the gear 24 is operated it will move the treadles, key slip, 75 and key lock simultaneously.

In order to properly conceal the treadles when they are in the retracted or inoperative position I have provided a door structure composed of the door sections 37 and 38 80 and the parallel horizontally extending tracks 39 which are mounted at 40 in the side frame structure of the case 1. The sections 37 and 38 are movable laterally to close the lower panel opening 5. These sections are 85 provided with beads running in the tracks and also one section is provided with a pin 41 projecting through a slot 42 in the upper track section 39, while the other door section 38 is provided on one edge with a hook 43. 90 A similar track structure and door sections 37' and 38' are mounted behind the upper panel for closing the tracker bar opening 4. The door section 37 of the lower door structure is connected to the door section 37' of 95 the upper structure by means of a cable 44 trained over the pulleys 45 and 45', the pulley 45' being swivelly mounted on said case so as to allow the upper panel to move outwardly into the position shown in dotted lines in Fig. 2 without disturbing the cable 44. Also the door section 38 of the lower door structure is connected by a cable 46 with the door section 38' of the upper door structure, the cable being hung on hook 43 100 and pin 41'. Also this cable 46 is trained over pulleys 47 and 47' similar in arrangement to the pulleys 45 and 45'. The door 38 of the lower door structure is also connected by a cable 48 running over a pulley 49 to the door section 37 of the lower door structure. Thus with this arrangement it will be seen that if any one of the door sections 37, 38 or 37', 38' is moved the complete set of door sections will be simultaneously moved 105 in unison and a corresponding amount. In order to provide for conveniently disconnecting these cables should it be desired to do so at points intermediate of their connection with the door sections, I have provided a cable coupling comprising the hook portion 50 and the eye portion 51 of the type shown 110 in Fig. 8.

As above stated, it is to be noted that both the upper and lower track structures which 115

carry the door sections are mounted on the case proper of the piano, and are entirely independent of the upper and lower panels 2 and 3, respectively. Also none of the mechanism for operating the door sections has any connection in any way whatsoever with either of these panels. Thus it will be evident that these panels 2 and 3 may be moved or removed at will without disturbing any 10 of the mechanism whatsoever, but will in fact, expose such mechanism to facilitate and afford access for adjustment of the same.

Now in order to operate the door sections at the proper time so that they will not interfere with the operation of the treadles, I have provided a lever 52 pivoted at 53 to a bracket 54 hung from the key bed structure. This lever 52 is rotatable about a fixed axis and has one end 55 arranged to slidably 20 and positively engage a pin 56 on the door section 38. The upper end of the lever 52 is provided with a toothed quadrant 57 engaging the gear 18 thus, as the lever 22 is moved thereby imparting motion to the gear 25 24 to operate the treadles, key lock and key slip, the pin 20 as soon as it reaches the end of the arcuate slot 21 in the gear 18 will cause the gear 18 to move, thus imparting motion to the toothed quadrant 57 and 30 through the medium of the lever 52 and its end 55 will impart motion to the door section 38. The door section 38 being connected with the other door sections by cables will impart motion to all of the door sections. 35 For instance, suppose the parts mentioned are in the relative position shown in Fig. 9, now if the handle 23 and its respective lever 22 are moved in the direction indicated by the arrow shown on the handle 40 the treadles will first move upwardly and inwardly within the case 1 into a retracted or inoperative position, at the time the treadles move the key lock and key slip will also move into their proper positions as indicated by the arrows, also at the time when 45 the treadles are within the case the gear 18 will begin to move and act upon the door section 38 to move it in the direction indicated by the arrow thereon, consequently, a 50 corresponding movement will be imparted, by reason of the cable connections, to the door sections 37, 37' and 38'. The door sections 37 and 38' will move in a direction opposite to the door sections 37' and 38 thus the tracker bar opening and treadle opening 55 will be closed by the door sections as soon as the treadles are in retracted positions. It will be evident that when the handle 23 and its corresponding lever 22 are moved in a 60 direction opposite to that indicated by the arrow on the handle 23 in Fig. 9 the parts comprising the arrangement will move in a reverse direction to that just outlined and 65 will move in consecutive order so that the door sections will first be opened and then

the treadles will be projected into the operative position through the treadle opening and the key lock and key slip will be simultaneously operated to their respective positions. 70

Referring particularly to the modified form shown in Figs. 10 to 14 inclusive, in which the door structures, door sections and treadles will be designated by the same characters of reference as hereinbefore used, the 75 operating mechanism comprises a shaft 58 journaled in the side members of the piano case as shown in Fig. 10. This shaft 58 carries an arm 59 which engages in a slot lost motion connection 60 on the end of a connecting rod 61 which is pivoted at its lower end to the bell crank 10 of the lever mechanism of the treadles. The shaft 58 carries a lever 62 which is connected by levers 63 and 64 to the key lock 32, and in this instance the key slip 32 and key slip 29 are not directly connected, but the shaft 58 carries at each end thereof levers 65 which connect with the connecting rods 66 having one pivoted to bell crank levers 67 mounted on 80 the piano case; also one end of each of the bell crank levers 67 is connected to the key slip 29 by means of the rods 68. Thus it will be seen that if the shaft 58 is rotated 85 motion will be imparted to the key lock, key slip and treadles simultaneously. Now in order to rotate the shaft 58 I have provided, according to the modified form of the invention, an arm 69 mounted on the said shaft 58 and having in its upper end an elongated slot 70, and mounted on a bracket 71 is a lever 72 pivoted at 73. This lever has an offset 74 to which is pivoted a link 75 having a bifurcated end 76 carrying a pin 77 which engages in the slot 70 of the lever 69; thus as the lever 72 is moved it will impart through the medium of the slidable connection of the levers 69 and 76 rotary motion to the shaft 58 in a direction corresponding to the direction in which the lever 72 is moved. Now for 100 operating the door sections a lever 78' is provided having at its lower end a slotted portion 78 slidably and positively engaging a pin 79 on one of the door sections 38. The lever 72 is extended at its rear end and has therein an arcuate slot 80 in which the end of the lever 78' rests thus providing a lost motion connection between the lever 72 and the doors. This lost motion connection is so arranged that the operation of the treadles and doors in consecutive order will be like that of the form shown in Figs. 1 to 9 inclusive, that is, in closing the instrument the treadles will be moved into the retracted or inoperative position before the doors begin to close, or in opening the instrument for automatic use, the operation will be vice versa in consecutive order. 105

In Fig. 12 I have shown another modified 110 form of pivoting the lever which provides 115

for a lost motion connection at the pivot point of the lever 72. This is taken care of by the cam surface 81 which as the lever moves engages with the lug 82. It may be 5 desirable in certain forms of piano construction to employ this rather than the form shown in Fig. 13.

While I have herein shown and described 10 specific forms of my invention, I do not wish 15 to be limited thereto except for such limitations as the claims may import.

I claim:—

1. An instrument case having an opening, 20 a door structure for said opening composed 25 of sections, pulleys mounted on said case, flexible means trained over said pulleys and connecting said sections, and means positively and slidably engaging one of said sections to move said door sections into a 30 closed position.

2. An instrument case including upper 25 and lower panels, each having an opening, doors for said openings, pulleys mounted on 30 said case, flexible means trained over said pulleys and connected to said doors for simultaneous movement when one of said doors is moved, and means engaging one of 35 said doors to move all of said doors into the open or closed position.

3. An instrument case provided with a removable panel wall having an opening therein, a door structure for said opening mounted for movement independent of the 40 position of said panel wall, and means for 45 operating said door structure to the open and closed positions.

4. An instrument case provided with a removable panel wall having an opening 45 therein, a door structure for said opening 50 mounted for movement independent of the position of said panel wall and composed of connected sections, and lever mechanism 55 positively and slidably engaging one of said sections to move said door structure into an 60 open or closed position.

5. In a player piano, a case including upper and lower panels, each having openings, doors for said openings, expression 65 levers, a key slip, a key lock, treadles movable through said lower panel opening into operative and inoperative positions, and means for operating said key slip and key lock and having lost motion connection with 70 said doors and treadles respectively whereby 75 said doors may be moved into an open position and the treadles then brought into an operative position, or vice versa.

6. In a player piano, a case including upper and lower panels, each having an opening, expression levers, a key slip, a key lock 80 positively connected with said cover for operation simultaneously therewith, treadles movable through said lower panel opening into operative and inoperative positions, and

means operating said key slip and key lock 85 and having lost motion connection with said doors and treadles respectively, whereby said doors may be moved into an open position and the treadles then brought into an operative position or vice versa. 70

7. In a player piano, a case including upper and lower panels each having an opening, doors for said openings, expression levers, a key slip, a key lock, treadles movable through 75 said lower panel openings into operative and inoperative positions, and means operating said key slip and key lock and positively and slidably engaging one of said doors to move all of said doors into an open or closed position. 80

8. In a player piano, a case including upper and lower panels each having an opening, mechanism including connected doors for said openings, expression levers, a key slip, a key lock, treadles movable through 85 said lower panel opening into operative and inoperative positions and means operating said key slip and key lock and connected with said mechanism for moving all of said doors into an open or closed position, and 90 moving said treadles into operative and inoperative positions.

9. In a player piano, a case including upper and lower panels having openings, doors for said openings, expression levers, a key 95 slip, a key lock, treadles movable through said lower panel opening into operating and inoperative positions, means for operating said key slip and key lock, and means for operating said treadles and doors synchronously with the operation of the key slip and key lock. 100

10. In a player piano, a case including upper and lower panels having openings, doors for said openings, expression levers, a key 105 slip, a key lock, treadles movable through said door panel openings into operative and inoperative positions, means for operating said key slip and key lock, and means for operating said treadles and doors consecutively with respect to each other and synchronously with the operation of said key slip and key lock. 110

11. An instrument case having an opening, treadles for projection through said 115 opening into and out of operative position, a door structure for said opening, shifting mechanism for said treadles and door structure including toothed gear driven connection with said structure and a lost motion 120 tooth geared drive connected with said treadles.

12. An instrument case having an opening, treadles for projection through said 125 opening into and out of operative positions, a door structure for said opening, and shifting mechanism for said treadles and door structure including toothed gear driven connection

nection with said structure and a lost motion toothed gear drive with said treadle, said gears being movable in the same direction.

13. An instrument case having an opening, treadles for projection through said opening into and out of operative positions, a door structure for said opening, and shifting mechanism for said treadles and door structure including rotatable toothed gear drive means for said door structure, and a lost motion rotatable toothed gear drive connected with said treadles.

14. An instrument case having an opening, treadles for projection through said opening into and out of operative positions, a door

structure for said openings, and shifting mechanism for said treadles and door structure including toothed gear driven connection with said structure, and a lost motion toothed gear drive connected with said treadles and driven from said toothed gear driven connection. 20

In testimony whereof, I have signed this specification in the presence of two subscribing witnesses.

WILLIAM J. CHERRY.
